[57] CLAIM

The ornamental design for wrist light, as shown and described.

DESCRIPTION

FIG. 1 is a perspective view of a wrist light showing my new design, the strap being shown in broken lines for illustrative purposes only;

FIG. 2 is a top plan view thereof;

FIG. 3 is a front elevational view thereof;

FIG. 4 is a rear elevational view thereof;

FIG. 5 is a bottom plan view thereof;

FIG. 6 is a left side elevational view thereof;

FIG. 7 is a right side elevational view thereof;

FIG. 8 is a top plan view of a second embodiment of my new design;

FIG. 9 is a front elevational view thereof;

FIG. 10 is a rear elevational view thereof;

FIG. 11 is a bottom plan view thereof;

FIG. 12 is a left side elevational view thereof;

FIG. 13 is a right side elevational view thereof;

FIG. 14 is a top plan view of a third embodiment of my new design;

FIG. 15 is a front elevational view thereof;

FIG. 16 is a rear elevational view thereof;

FIG. 17 is a bottom plan view thereof;

FIG. 18 is a left side elevational view thereof; and,

FIG. 19 is a right side elevational view thereof.
